UNITED STATES PATENT OFFICE.

JOSEPH J. HOLLAND, OF BRYAN, TEXAS.

COMBINED CORN AND COTTON-SEED PLANTER.

SPECIFICATION forming part of Letters Patent No. 274,195, dated March 20, 1883.

Application filed February 6, 1882. (No model.)

To all whom it may concern:

Be it known that I, JOSEPH J. HOLLAND, a citizen of the United States, residing at Bryan, in the county of Brazos and State of Texas, have invented new and useful Improvements 5 in a Combined Corn and Cotton-Seed Planter, of which the following is a specification.

This invention relates to a cotton-seed and corn planter which by certain alterations in 10 some of its parts will be readily converted into a plow or analogous implement.

Prior to my invention the seeding-wheel has been provided with one or more recesses in its 15 perimeter, the depth of which said recess or recesses has been rendered variable by means either of a false bottom adjusted toward or away from the bottom of the recess by means of a set-screw, or by means of overlapping disks adjustably secured within the recess; 20 but in such seeding-wheels, while the depth of the recess is rendered variable the width thereof remains unchanged.

It is the object of my invention to simplify 25 the means employed for providing at will recesses of different depths in the wheel, and also to provide means whereby a recess of both greater width and depth can be provided for cotton-seed than for corn, whereby the cotton-seed can be fed from the hopper in 30 a more certain, free, and efficient manner than heretofore. In the instances mentioned the recesses are not concave or segmental-shaped, but in the nature of cylindrical recesses, while in my seeding-wheel the recesses are segment- 35 al-shaped, or concave, as will be seen fartheron.

To attain the objects of my invention I form 40 the seeding-wheel with a peripheral series of concave or segmental-shaped recesses, and for each recess provide a segmental block formed 45 with a small recess for corn, the block being detachably secured in the concavity in the wheel by a screw passing through the bottom of the recess on the segmental block, the said block fitting in and filling the concavity in the 50 wheel, and being formed so that its face shall be flush with the face of the wheel, whereby when the block is fitted in the concavity the recess shall be adapted for corn, and when detached the concavity will afford a deeper and

in after more fully described, and illustrated in the drawings, in which—

Figure 1 represents a plan view of a machine embodying my invention; Fig. 2, a longitudinal sectional view, and Fig. 3 a transverse 55 sectional view, of the seeding-wheel on an enlarged scale.

The letters A A designate the two side beams, and B B the two end cross-beams, which constitute the main frame of my combined cotton-seed and corn planter. The two side beams are adapted to be set at a variable distance apart, since the end beams pass through mortises which are made through the side beams, holes a a being formed in the end 60 beams, and pins b b passed through the side beams into said holes.

C indicates the axle, and D D the supporting-wheels, alongside of one of which wheels is a large cog-wheel, D', and alongside of the 65 remaining one of said wheels is a plain-faced wheel, D''. The cog-wheel D' gears with a smaller cog-wheel, D³, which is arranged just 70 in advance of it, and which is mounted upon one end of an axle, E. This axle projects from 75 both sides of the machine and has its bearings beneath the side beams. Upon that end of the axle which is opposite to the end upon which the small cog is mounted is secured a small plain-faced wheel, D⁴, which 80 bears against the large plain-faced wheel D'', in order to steady the axle upon which these 85 two small wheels are mounted. Upon this said axle E is secured the seeding-wheel F, which serves to agitate the seed with in a hopper, G, and to convey the seed out from the said hopper and drop the same. This 90 seeding-wheel is peculiarly constructed. It has a series of segments, g, set into a series of circumferential concave recesses, f, and each 95 segment has a hole, h, bored in it to a certain depth. The screws or bolts g', which secure these segments to the wheel, are passed down through the holes h, and then through the segments into the wheel. The screws are set far 95 enough down to leave said holes open to receive corn, which drops into them and is carried out of the hopper and dropped; but when cotton-seed is to be planted the segments are taken from the wheel, the number 100

taken off depending upon the rapidity with which it is desired to effect the seeding.

H designates the opener in advance of the seeding-wheel, and I I indicate the shovels for covering up the seed. These are detachably secured to the main frame, so that when the machine is to be employed as a subsoil-plow the standards of the shares can be readily connected with the machine in place of the opener 10 and shovels which are used in connection with the seeding-wheel.

The hopper G is detachable from the machine in order that it can be detached when the machine is to be used for plowing, breaking land, or for other purposes. To this end the hopper is secured to a base, G', which is secured by bolts G² to the end beams of the machine. The advantages of removing the hopper will be apparent, since it relieves the machine of an unnecessary incumbrance; and, further, a chopper may be attached to the rear axle for the purpose of chopping out cotton.

Mortises K K are made in the side beams to receive the standards of extra plowshares. 25 These plows can be arranged in a variety of ways, according to the uses of the machine, such arrangements being a matter of judgment with the operator.

When the machine is used for dropping cotton-seed or corn two handles will be secured by braces L L at the rear end of the side beams; but when the machine is used as a plow but one handle will be required.

M designates the clevis, secured so as to be 35 adjusted either to the right or the left.

I propose providing suitable brace-rods for the standards of the shovels or openers, and to so connect them with the standards that they can be readily detached.

It will be understood that I do not limit myself to the number of plows or shovels. I may so construct the beams that three openers and three shovels can be employed, and so that they can be properly arranged on the beams 45 with relation to each other.

It will be seen that the segmental blocks can be fitted in the concave recesses in the wheel with common wood-screws, which can be screwed down so that their heads will not occupy any material portion of the recess in the blocks; but in the other cases hereinbefore mentioned, where the recess has an adjusta-

ble false bottom, bearings must be provided for the screws, and the latter must be in the nature of set or thumb screws, thus entailing 55 expense and clogging up the recesses; also, while in such cases the depth of the recess can be varied its width will remain the same; but for cotton-seed a wider recess is desirable, and hence by my cheap and simple device I attain 60 both features.

Heretofore a cotton-seed planter has been provided with a removable seed-dropping cylinder having teeth which draw the seed from a hopper and drop the same into a spout. In 65 using said machine for planting corn, beans, or the like, the toothed cylinder is removed, and a cylinder provided with a peripheral series of cup-shaped recesses substituted therefor. A cup is secured in each one of said recesses, and for different kinds of grain cups having different-sized cavities are employed; but in such machines the recesses in the cylinder have straight walls, and are not segmental-shaped, as in mine, and they are not 70 adapted to be used for planting cotton-seed, the toothed cylinder being used when cotton-seed are to be planted.

What I claim is—

In a combined corn and cotton-seed planter, 80 the combination, with the hopper, the opener, and the coverers, of the seeding-wheel F, formed with a peripheral series of segmental-shaped recesses, f, and the segmental blocks g, each formed with a recess, h, and detachably secured in a concavity in the wheel by a screw, g', passing through the bottom of the recess in the block, the said block fitting into and filling the concavity in the wheel, and being also formed so that its face shall be flush 85 with the face of the wheel, whereby when the block is in place the recess in the same will be brought into use, and when detached the entire concave recess in the wheel will be used, 90 as and for the purpose specified.

In testimony whereof I have hereunto set my hand in the presence of three subscribing witnesses.

JOSEPH J. HOLLAND.
